UNITED STATES PATENT OFFICE

JOHN C. ANDERSON, OF KEYPORT, NEW JERSEY

CONVEYER BELT

Original application filed July 23, 1927, Serial No. 207,844. Divided and this application filed April 2, 1929. Serial No. 351,857.

This application is a division of a co-pending application Serial No. 207,844, filed by me in the United States Patent Office on July 23, 1927.

5 My invention relates to conveyers, and more particularly to those of the woven wire type, such as are formed by helically interlaced strands of wire that are disposed transversely of the longitudinal axis of the belt, as shown for example, in Patent No. 1,583, 10 048, issued to Henry W. Ingle on May 4, 1926.

In this type of conveyer belt, the helices produce a diagonally ribbed surface which 15 tends to cause the belt to creep laterally when passing around rollers or over supporting surfaces. Heretofore, efforts have been made to overcome or counteract this 20 tendency of the belt to creep in one lateral direction, as by dividing the belt into sections which are placed end to end to form the belt, the strands of certain sections being in the form of left hand helices and the strands of other sections being in the form 25 of right hand helices, but it will be seen that in such structures there is tendency to displacement of the belt laterally on zigzag lines.

Stated broadly, my invention contemplates the provision of belt sections that are 30 divided on a line extending longitudinally of the belt, and has for one of its objects the provision of a belt of the character referred to wherein the form of connection is 35 such as to render the belt readily flexible in passing around pulleys or rolls even of relatively small diameter, and wherein there is no substantial amount of driving strain imposed upon the connection between the 40 belt sections.

Another object of my invention is to simplify and improve generally belt structures of the type referred to.

A form which my invention may take is 45 shown in the accompanying drawings, wherein

and left hand weaves, respectively, and showing the tendency of the sections to creep in diagonally-opposite directions; and

Fig. 2 is a view showing a manner in which the sections may be joined without the 55 necessity of employing an additional connecting member.

In assembling the mesh structures 6 and 7 to form a conveyer belt, I prefer to so place them that their ribbed surfaces, which 60 ordinarily have contact with the rollers (not shown), will extend diagonally as indicated by the diagonal lines of Fig. 1. By this arrangement, when the belt is driven in the direction indicated by the arrow in Fig. 1, 65 the sections will tend to creep in the directions indicated by the arrows in Fig. 2, thereby exerting a tensional force upon the connection between the sections, so that the belt will lie flat. If the diagonal lines 70 converged with respect to the path of travel of the belt, as in case the belt were driven in the direction opposite to that indicated by the arrow in Fig. 1, the sections would tend to move toward the longitudinal center line 75 of the belt and exert a compressive force at their line of juncture, thereby causing the belt to bulge at its mid portion, which would not only create an undesirable distortion of the belt, but result in upsetting 80 or displacement of the glassware or other articles conveyed thereby.

The strands of adjacent belt sections are directly connected to one another, by so bending the ends of adjacent strands of 85 the respective belt sections that they have flexible interlocking connection with one another, as shown at 11 and 12. The belt may bend readily in passing around a roller, and there is no great driving strain imposed 90 upon the connecting means. The joints 11 and 12 are so formed that they will not project above the upper plane of the belt. By avoiding a ridge or depression along the line of juncture of the belt sections, a more 95 nearly level surface is provided for receiving glassware or other articles, thus avoiding the tipping over of the same.

Each strand of helical wire is connected to one strand of the adjacent section of the 100

Figure 1 is a diagrammatic view that is representative of a conveyer belt made of two sections divided on a line extending longitudinally of the belt that have right

belt and forms a substantial continuation thereof, the two aligned strands becoming in effect one transverse strand having one-half formed with a right hand twist and the other half formed with a left hand twist. Thus there is no relative movement between the aligned strands, as the belt is flexed by the driving means to cause it to pass around a roller. By this construction, wear at the connection will be minimized and any tendency toward distortion or creeping of the belt, due to a relative movement of two connected strands out of alignment transversely of the belt, will be eliminated. The sections are connected only by the connection of aligned strands.

It is to be understood that the above described embodiment of my invention is for the purpose of illustration only, and various changes may be made therein, without departing from the spirit and scope of the invention.

The term helical, as applied to the wires described herein and as that term is used in the claims, is not to be construed as limited to wires which are wound in true helixes but is to be construed broadly enough to cover, for example, wires which are wound as a helix and flattened to some extent in the planes of the top and bottom of the belt.

I claim as my invention:

1. A woven wire conveyer composed of two longitudinal sections joined together substantially at a longitudinal center line of the conveyer, each section being composed of a plurality of interwoven helically wound wires extending transversely of the section, the wires of one section having a right hand twist and those of the other section having a left hand twist, the said belt being assembled with adjacent wires of the two sections in line transversely of the belt, the inner ends of each pair of adjacent wires being directly connected together independently of the connection between other wires.

2. Conveyer belt structure comprising a plurality of pairs of helical strands, each pair of strands comprising one strand of right hand twist and one strand of left hand twist aligned transversely of the belt, one end of each strand being connected to an end of the aligned strand, each pair being interwoven with the adjacent pairs of wires, and the connection between the wires of each pair being independent of the connections between other pairs of wires.

3. A conveyer belt composed of two longitudinally extending sections, each section composed of helical members extending crosswise of the section and interlocking, the members of one section being reversely arranged to those of the other section with the members of the sections arranged in rows, and the members of one section in alignment with those of the other section, and an im-

mediate and independent connection between the inner end of each member of one section, with the inner end of the aligned member of the other section.

Signed at Keyport, New Jersey, this 21st day of March, 1929.

JOHN C. ANDERSON.
